UNITED STATES PATENT OFFICE.

FRANK SIKORSKI, OF BRIDESBURG, PENNSYLVANIA.

STABILIZING DEVICE FOR AEROPLANES.

Application filed July 13, 1926. Serial No. 122,126.

The present invention relates to a stabilizing device for use in connection with aeroplanes and the like, and aims to provide a novel and improved device of this character which can be conveniently arranged for efficiently righting or stabilizing an aeroplane should the same become beyond control.

Another object of the invention is to provide a device as above mentioned having a telescopic member provided with a heavy weight on its lower end which may be spaced rigidly below the fuselage of an aeroplane for balancing the same or may be drawn upwardly in close proximity to the fuselage when not in use so as not to interfere with proper landing of the aeroplane.

A further object of the invention is the provision of a tubular telescopic member having air-tight connection so that air under pressure may be released into said tubular telescopic member for forcing the weight to extended position, and an air controlled means for drawing the sections of the telescopic member and weight upwardly when not in use.

A still further object of the invention is to provide a weighted lever for controlling the position of the weight carried by the telescopic member so that when the aeroplane is in an improper flying position, the weighted lever can be manually operated or will automatically swing to extend the stabilizing weight.

It is also an object of the invention to provide a device of the above indicated character, which is relatively simple, substantial in construction, which can be manufactured at a relatively low cost, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a side elevation of an aero-

plane, showing my improved stabilizing device arranged thereon,

Figure 2 is a fragmentary elevation of the lower portion of the stabilizing device,

Figure 3 is a longitudinal section through the telescopic stabilizing device showing the same in raised position.

Figure 4 is a fragmentary longitudinal section through the fuselage of an aeroplane showing the means for operating the stabilizing device in section,

Figure 5 is a horizontal section taken on line 5—5 of Figure 4, and

Figure 6 is a section through the valves for controlling movement of the stabilizing device.

Referring to the drawings, the numeral 10 designates the fuselage of an aeroplane, which has extending vertically therethrough and slightly at an angle a tubular member 11. The tubular member 11 is secured rigidly in the fuselage 10 and has its upper end closed by means of a closure cap 12 which is secured to the upper wing 13 of the aeroplane. The lower end of the tubular member 11 protrudes slightly below the fuselage, as at 14.

The above mentioned tubular member 11 comprises the upper of a series of tubular members which are slidably arranged in each other so as to provide a telescopic supporting structure. As a matter of illustration, four tubular members are shown and designated by the numerals 11, 15, 16, and 17. The tubular members are of different sizes, the smallest being at the bottom and the largest at the top when the supporting structure is in extended position. At the lower ends of the tubular members 11, 15, 16, and 17 are provided inwardly extending annular flanges, as indicated by the numeral 18 which are adapted to engage with outwardly extending annular flanges 19 arranged upon the upper ends of the sections 15, 16, 17, and a rod 20 which is slidably arranged in the lowermost tubular member 17. In each of the flanges is arranged an annular groove for receiving a ring so as to form air-tight connection between the various tubular members and the rod 20.

On the lower end of the rod 20 is provided

a weight 21 which is constructed of a shape so as to eliminate as much resistance as possible while the aeroplane is in motion. By referring to Figure 1 of the drawings, which 5 shows the tubular members and rod 20 in extended position, it can be seen that the weight 21 is positioned so as to stabilize or properly balance the aeroplane. Arranged on opposite sides at the lower ends of each 10 tubular member 11, 15, 16, and 17, are eyes 22 through which extend a pair of cables or the like 23, the cables being arranged upon opposite sides of the tubular members and having their lower ends attached to 15 eyes 24 carried by the weight 21. The cables 23 after passing through the eyes 22 arranged upon the lower end of the uppermost tubular member 11 are arranged about pulleys 25 and have their opposite ends secured to a pair of winding drums 26 rotatably mounted by depending brackets 27 secured to the lower surface of the fuselage 10.

Mounted on the shaft which rotatably 20 mounts the drum 26 and between the pair 25 of drums 26 is an intermediate drum 28 of smaller size. The intermediate drum 28 has wound thereabout an endless cable 29 which is also arranged about a pair of pulleys or 30 rollers 30 carried by the fuselage and spaced forwardly and rearwardly of the intermediate drum 28. Secured to the fuselage of the aeroplane arranged above the intermediate drum 28 and between the pulleys 30 is a cylinder 31 having a piston 32 arranged 35 therein which in turn has a connecting rod 33 attached thereto which extends rearwardly and out of the cylinder through a packing box 34. Attached to the rear end of the rod 33 is a clamping element 35 which is also attached to the endless cable 29. From the foregoing, it can be seen that 40 when the piston is moved within the cylinder that the endless cable will be either pulled forwardly or rearwardly, thus causing 45 turning movement of the intermediate drum 28 which in turn will cause the winding drums 26 to turn thus drawing in on the cables 23 or unwinding the cables 23 from said winding drums.

50 Positioned in the fuselage 10 of the aeroplane is a pair of compressed air tanks 36 and 37. The tank 36 is in communication with the cylinder 31 by means of piping 38. The tank 36 communicates with the cylinder 55 32 at the end thereof opposite to that through which the rod 31 extends. The tank 37 is in communication with the upper end of the tubular member 11 by means of piping 39. In the piping which leads from each 60 of the tanks 36 and 37 to the cylinder 31 and the tubular member 11 is a valve 40. The valves 40 are each provided with small crank levers 41 thereon which are connected to a rod 42 which has its forward end 65 connected to a lever 43 pivotally mounted

in the fuselage 10 of the aeroplane. On the lower end of the lever 43 is a weight 44 for normally holding the lever 43 in upright position with the passageways in the valves 40 out of alignment with the piping. 70 Each of the valves 40 has an outlet opening 45 therein so as to permit the escape of air from the cylinder 32 and the tubular telescopic member at the proper time so as to relieve pocketing of air in said cylinder and tubular telescopic member. The valves 40 are so constructed and connected together that when one valve is opened so as to permit air to pass from one tank to either the cylinder or the tubular telescopic member, 80 the outlet openings will be in proper alignment so as to permit the escape of air from the other of said elements so that when the tubular telescopic member is extended, the piston 32 will be permitted to return to the air inlet end of the cylinder and when the piston is forced to the opposite end of the cylinder, the air in the tubular telescopic member will be permitted to escape so that said telescopic member can be raised 90 to position the weight 21 in close proximity to the fuselage.

In operation, when the aeroplane is in flight and the aeroplane should start slipping or tilting about a horizontal axis or turning turtle, the lever 43 may be easily pulled forwardly so as to align the openings in the valves 40 arranged in the piping from the air compressing tank 37 to the tubular telescopic member so as to force said telescopic member in extended position and arrange the weight 21 in a rigid manner spaced a sufficient distance below the aeroplane to cause the righting of the plane. When the valve 40 is opened so as to permit the extending of the telescopic tubular member, the other valve 40 which is in the piping that communicates the tank 36 with the cylinder 31 is moved so as to permit the air pocketed in the cylinder to escape from the valve, thus permitting the piston 32 to move to the proper end of the cylinder 31. After the aeroplane has been righted and the equilibrium is maintained, the weight 21 may be drawn upwardly to a position close to the lower portion of the fuselage 10 by swinging the lever 43 in the opposite direction. By such movement of the lever, air will be permitted to enter the cylinder 31, thus forcing the piston 32 to the opposite end thereof which in turn will cause the endless cable 29 to be pulled so as to turn the intermediate drum 28, such turning movement of the intermediate drum causing the winding drums to be turned which will wind the cables 23 up and on the same, thus drawing the telescopic members upwardly and into each other, as shown in Figure 3 of the drawings. When the weight is in a drawn up or upper position, the structure for op-

erating the same and the weight itself will not interfere with proper landing of the aeroplane.

The device may also be used in connection 5 with determining the distance to the ground at night time when it is desired to make a landing. By extending the weight to its lower position, the aviator may gradually permit his machine to come nearer to the 10 ground until the weight 21 comes in contact with the ground. At such time, he may easily draw the weight upwardly and knowing the distance the aeroplane is from the ground, he may make a proper landing.

15 By providing the weight 44 on the end of the lever 43, said weight will cause the lever to swing should the aeroplane be tilted at an angle where the flying thereof has become dangerous, thus causing operation 20 of the valves 40 so as to automatically extend the weight for righting the plane or obtaining the equilibrium thereof.

Having thus described my invention, what I claim as new is:

25 1. A stabilizing device for aeroplanes comprising a tubular telescopic member carried by the aeroplane, air-tight connection between the sections of said tubular telescopic member, a weight arranged upon the lowermost section of said telescopic member, means for forcing air under pressure to said tubular telescopic member so as to extend the same to position the weight spaced from the aeroplane, and means for drawing said 30 telescopic member inwardly so that said weight lies in close proximity to the aeroplane.

40 2. A stabilizing device for aeroplanes comprising a tubular telescopic member carried by the aeroplane, air-tight connection between the sections of said tubular telescopic member, a weight arranged upon the lowermost section of said telescopic member, means for forcing air under pressure to said tubular telescopic member so as to extend the same to position the weight spaced from the aeroplane, cables attached to said weight and extending along said 45 telescopic member, and means attached to said cables for drawing in thereon so as to telescope said telescopic member to position the weight in close proximity to the aeroplane.

50 3. A stabilizing device for aeroplanes comprising a tubular telescopic member carried by the aeroplane, a weight arranged upon the lowermost section of said telescopic member, means for supplying air under pressure to the uppermost section of said 55 telescopic member in order to force the other sections downwardly to extend the weight spaced from the aeroplane, a cylinder carried by the aeroplane, a piston slidably arranged in said cylinder, cables attached to said weight and extending along said 60 telescopic member.

scopic member, means attached to said piston for drawing in said cables, and means for supplying compressed air to said cylinder for sliding said piston therein.

4. A stabilizing device for aeroplanes comprising a tubular telescopic member carried by the aeroplane, a weight arranged upon the lowermost section of said telescopic member, means for supplying air under pressure to the uppermost section of said 70 telescopic member in order to force the other sections downwardly to extend the weight spaced from the aeroplane, a cylinder carried by the aeroplane, a piston slidably arranged in said cylinder, cables attached to 75 said weight and extending along said telescopic member, means attached to said piston for drawing in said cables, means for supplying compressed air to said cylinder for sliding said piston therein, a pair of valves 80 arranged for controlling the flow of air to said tubular telescopic member and to said cylinder, and means connected to said valves for opening one valve upon closing of the other so as to extend said telescopic member 85 from the aeroplane or draw the same upwardly so that the weight will lie in close proximity to the aeroplane.

5. A stabilizing device for aeroplanes comprising a tubular telescopic member carried by the aeroplane, a weight arranged upon the lowermost section of said telescopic member, means for supplying air under pressure to the uppermost section of said 90 telescopic member in order to force the other sections downwardly to extend the weight spaced from the aeroplane, a cylinder carried by the aeroplane, a piston slidably arranged in said cylinder, cables attached to 95 said weight and extending along said telescopic member, means attached to said piston for drawing in said cables, means for supplying compressed air to said cylinder for sliding said piston therein, a pair of valves 100 arranged for controlling the flow of air to said tubular telescopic member and to said cylinder, and means connected to said valves for opening one valve upon closing of the other so as to extend said telescopic member 105 from the aeroplane or draw the same upwardly so that the weight will lie in close proximity to the aeroplane.

110 6. A stabilizing device for aeroplanes comprising a telescopic member carried by the aeroplane, a weight arranged upon the lower section of said telescopic member, means for extending said telescopic member so that the weight is spaced below and from the aeroplane, cables attached to the weight and extending along the telescopic member, a pair of winding drums having said cables 115 attached thereto, another drum mounted 120

125

130

135

upon the same shaft said winding drums are mounted on and secured thereto, pulleys spaced from said second mentioned drum and at each side thereof, an endless cable extended over said pulleys and trained around said second mentioned drum, a cylinder carried by the aeroplane, a piston mounted in said cylinder, means attached

to said piston and to said endless cable for causing said endless cable to be moved upon movement of the piston in the cylinder, and means for supplying air to said cylinder for sliding the piston therein.

In testimony whereof, I have affixed my signature.

FRANK SIKORSKI.
